UNITED STATES PATENT OFFICE

2,276,089

RECOVERY OF SOLVENTS FROM OILS

Edward G. Ragatz, San Marino, Calif., assignor to
 Union Oil Company of California, Los Angeles,
 Calif., a corporation of California

Application June 26, 1937, Serial No. 150,658

5 Claims. (Cl. 202—61)

The present invention relates to methods of and apparatus for evaporating, and more particularly pertains to systems employed for recovering solvents from products produced by extraction processes. Specifically, the invention covers the regulation and control of the multiple evaporating systems employed for the recovery of solvents which have been or are being used for extraction purposes, as for example, in the solvent extraction of petroleum oils to produce fractions which are respectively more and less paraffinic in nature than the oils treated.

It is an object of this invention to provide a process and system for the recovery of the solvents from oils with maximum efficiency and with minimum loss of solvent. Another object is to provide a system of this type which will produce a high degree of control, particularly as to the temperature and pressure conditions, thus providing for a high degree of economy in the utilization of heat and in the recovery of the solvents. Still further objects of the invention will be apparent from the following description.

The solvent treatment of various types of oils is now quite well known in the art. Some of these processes remove the oils, whether animal, vegetable or mineral, from the solids in which they are found. In other cases and this is particularly true in the case of a mineral oil, a solvent treatment is employed to reject such substances as asphalt and/or wax originally present in the oil and detrimental to its use, particularly when the mineral oil is of the lubricating oil type. As previously stated, a further example of solvent extraction process is one in which a mineral oil fraction is separated into two or more components on the basis of the selective solvent power of the solvent. Processes of this type have been used for the treatment of motor fuel stocks, kerosene stocks and particularly lubricating oil stocks, in the latter case the solvent extraction producing components which are respectively more and less paraffinic in nature than the original lubricating oil treated. When a lubricating oil stock is treated with solvents such as liquefied normally gaseous hydrocarbons, phenol, cresylic acid, nitrobenzene, etc., whether alone or in combination with other solvents such as benzol, under temperature and pressure conditions such as to form at least two liquid phases, as a general rule one of these phases usually termed the "extract phase" contains a greater amount of the solvent employed and the relatively more soluble portion of the oil, while the other phase known as the raffinate phase com-

prises a lesser amount of the solvent together with the less soluble portion of the oil. When the solvent is removed from the extract and raffinate phases the oil constituents contained therein are respectively known as extract and raffinate.

Although the process and system presented hereinbelow will be described in conjunction with the recovery of the solvent from either the extract or raffinate phases of the above type of solvent extraction, it is to be understood that the invention is equally applicable to solvent recovery from any type of process in which a solvent has been used for the separation or extraction of any type of materials regardless of their source. The details of the invention will become apparent from the description presented hereinbelow, particular reference being made to the drawing, which represents diagrammatically

20 two embodiments of the process and in which: Fig. 1 shows a conventional two-stage evaporating system employed for the recovery of solvent vapors from the extract phase produced during the solvent extraction of a lubricating oil stock, said system embodying the features of the present invention, and

25 Fig. 2 is a similar embodiment of the invention as applied to a single-stage evaporating system of the above type.

30 Referring now to the drawing and more particularly to Figure 1, the extract phase comprising a mixture of oil and solvent is introduced into the solvent recovery system through line 10 from a source not shown in the drawing. For

35 the purpose of heat economy, this stock is advantageously compressed, as for example to a pressure of approximately 200-215 lbs. per square inch. Before entering the first evaporator the stock first passes through a preheater 11 and

40 then, after passing through line 12, is further heated in 13 which is a heater employing steam for the indirect heating of the stock passing therethrough. After leaving preheater 13 the stock passes through line 14 and enters the first

45 or high pressure evaporator 16, in which a portion of the solvents are evaporated from the mixture. In the specific example in which the solvent-oil mixture was compressed to approximately 200-215 lbs., the evaporator or separator 16 is maintained at approximately that pressure.

50 The oil and the solvent still remaining liquid at the temperature and pressure conditions maintained in separator 16 leave said evaporator through line 17 and are conveyed to the second or low pressure evaporator 18 in which

the pressure is considerably lower than that maintained in the first separator. This is realized by the maintenance of a reducing valve 19 in line 17, the opening of said valve being regulated and/or actuated by the liquid level in the high pressure evaporator 16. The oil-solvent mixture being conveyed through line 17 to the low pressure evaporator 18 passes successively through a heat exchanger 21 and then through a steam heater 22. The solvent vapors separated in the high pressure evaporator 16 leave the latter through line 25, are conveyed first through heater 21 to preheat the solvent-oil mixture being conveyed to the low pressure evaporator, then through line 26 through the heat exchanger 11 on line 10, and are then withdrawn through line 27. The condensed and uncondensed solvent mixture, passing through line 27, is then conveyed into separator 28 wherein the vapors are separated from the liquefied solvent, the former leaving through line 30 while the latter is withdrawn through line 31.

By virtue of the pressure and temperature conditions maintained in 18, the oil-solvent mixture introduced thereto separates into its constituent components, the oil leaving said separator through line 33 controlled by float valve 34, while the deoiled solvent vapors leave the separator through line 35. These vapors as well as the vapors passing through line 30 are then liquefied in a condenser 36, and may then be used again for solvent extraction purposes. For this purpose they may be employed alone or mixed with the liquid solvents coming through line 31.

The system illustrated and described hereinabove, however, is extremely unstable as to temperature, pressure, and ratios of vapors to condensate. In fact this system is impractical in view of its relatively high utilization of heat. Thus, any variation in the amount of heat conveyed in steam heater 13 to the stock being transmitted to the high pressure separator, causes the evaporation of a relatively increased amount of solvent vapors, which leave said separator through line 25 and are conveyed through line 26 to the heat exchanger 11. This further heats the extract phase or stock being conveyed through the system, thus tending to further raise its temperature. Simultaneously, or immediately thereafter, the increase in pressure in the high pressure evaporator 16 tends to create a back pressure on line 14, thus reducing the quantity of feed stock entering said separator. Obviously, such a decrease in the rate of throughput in turn results in a decrease in the quantity of solvent vapors evaporated in the separator and conveyed through lines 25 and 26 to the heat exchanger 11. This causes a substantial reduction in the heat imparted to the incoming feed stock, thereby substantially lowering the temperature of said stock when it enters separator 16. It is thus seen that the operating conditions of the system are such that they tend to oscillate constantly from one extreme to the other. It is therefore a further object of the present invention to avoid the above described defects and to provide a system whereby said operating conditions may be adequately and perfectly controlled, thereby stabilizing the conditions and avoiding excessive heat utilization and/or incomplete solvent recovery.

To avoid the above defects and disadvantages, applicant has discovered that it is necessary to provide the above or similar systems with a cer-

tain combination of controls. Thus, it has been found that a substantially complete control may be established by providing vapor line 30 with a back-pressure regulator (indicated by numeral 39), and by regulating the introduction of heat to steam heater 13 so that the quantity of vapors passing from separator 28 through said back-pressure regulator 39 on line 30 is at a minimum, or at least within a certain minimum range. Such a regulation, which obviously may be realized either automatically or manually, will produce an optimum heat efficiency, and will, together with other controls to be described hereinbelow, result in the establishment and maintenance of constant and stable conditions in the solvent recovery system.

Referring again to Figure 1 and for the purpose of accomplishing the above results, steam line 40, employed for the introduction of steam to heater 13, is provided with a valve 41, which, as previously stated, may be of the manually actuatable type, but which, in the preferred embodiment is automatic and, as shown, responsive to the rate of flow of vapors through line 30 upstream of back-pressure valve 39. For this purpose, line 30, upstream of valve 39, is provided with an orifice meter 38, and valve 41 is connected by means of a pipe 42 with said meter 38 so that valve 41 is thus actuatable responsive to the volume of the vapors passing through line 30. Obviously, valve 41 can thus be set so that the introduction of steam through line 40 into heater 13 will be such that the vapors passing through line 30 are held to a minimum, and so that any variation in the quantity of these vapors will correspondingly vary the rate of said steam introduction. It is obvious that regulation of heat supply to the system so that the quantity of vapors passing through line 30 are maintained at a minimum, is only for the purpose of realizing optimum heat efficiency. Therefore, if conditions in the system are such that it is more economical to use a greater quantity of heat, such a condition may result in a greater flow of vapors through line 30. Whatever this may be, the provision of valve 41 on steam line 40 and the regulation of said valve in response to fluctuations in rate of flow through line 30 upstream of back-pressure valve 39, will result in the maintenance of stable conditions in the system by regulating the temperature and pressure conditions so that the above described flow of vapors through line 30 is maintained at the given constant. In view of the fact that there is a certain lag in the system, it is preferred to regulate valve 41 in response to the flow through meter 38, the arrangement or setting being such that the rate of flow through line 30 may vary within a certain predetermined range before valve 41 on steam line 40 is actuated. Obviously, however, in some instances the regulation of valve 41 may be made to be responsive to pressure changes in line 30.

For the purpose of further control of the conditions in the above-described multi-stage solvent recovery system, it is essential to maintain the feed constant. For this purpose, line 10 is provided with a valve 44 adapted to maintain the rate of flow of solvent-oil through line 10 constant. Further stabilization is realized by providing a back-pressure valve 46 on the vapor line 35 leading from the low pressure separator 18 to condenser 36.

The following is a specific example of an operation carried out in the above multi-stage recovery system, this example being non-limiting

in scope, but merely for purposes of a clearer understanding of the advantages derived from the present invention. Also, although the example is described in connection with the recovery of a sulphur dioxide solvent from the extract phase obtained from the extraction of lubricating oils with said solvent, it is clear that the invention can be used in connection with the removal of any solvent from other materials regardless of the source thereof, and whether it be an extract or raffinate phase.

An extract phase, which in the instant case may consist of approximately 16% extract and 84% liquid sulfur dioxide, is continuously fed, at a pressure of 215 pounds gauge, into the system through line 10, valve 44 maintaining said rate of input constant. In heat exchanger 11 this feed stock is raised to a temperature of about 145° F., while after passage through steam heater 13 it is raised to a temperature of approximately 165° F., at which temperature (and at a pressure of about 200 pounds gauge) said extract phase enters the high pressure separator 16. Under the enumerated conditions, slightly over one-half of the sulfur dioxide is evaporated at this stage of operations, these vapors being removed or withdrawn from separator 16 through line 25. The liquid phase is then withdrawn from said separator through line 17, the rate of withdrawal being regulated by valve 19 in response to the position of float 20 in separator 16. After passing through valve 19, this liquid phase is conveyed, at a pressure of about 80 pounds and a temperature in the neighborhood of 112° F., to heat exchanger 21, wherein it is brought in indirect heat exchange with the sulfur dioxide vapors withdrawn from the above described high pressure separator 16. In this heat exchanger the oil-solvent mixture is raised to a temperature of about 145° F., while the sulfur dioxide vapors are thereby cooled to about 160° F. The oil-solvent mixture is then conveyed through steam heater 22 wherein it is further heated so that said mixture is at a pressure of about 72 pounds and a temperature of approximately 300° F. when it enters the low pressure separator 18, and wherein substantially all of the sulfur dioxide is separated from the extract. The solvent vapors are then withdrawn through line 35 equipped with a back-pressure valve 46 and are conveyed to condenser 36 of any well known type. The extract thus freed from the solvent is continuously withdrawn from the low pressure separator 18 through line 33, the rate of removal being automatically regulated by the float controlled valve 34.

The vapors of sulfur dioxide withdrawn through line 25 from the high pressure separator 16, after passing through heat exchanger 21 as aforesaid, are then conveyed through line 26 to heat exchanger 11 wherein they preheat the incoming fresh feed stock. Thereafter, these vapors, cooled to about 160° F., are passed through line 27, and enter separator 28 wherein the condensed portion of the sulfur dioxide separate from the vapors. The condensate is then removed through line 31 controlled by the float actuated valve 32, while the vapors may be conveyed to condenser 36 through line 30 equipped with a back-pressure valve 39.

It is easily seen that the above described arrangement permits a thorough control of conditions in the system. Thus, by maintaining constant the rate of feed into line 10, and by setting the various valves for an optimum operation of the system, it is possible to obtain optimum and

economic heat utilization. Also, any change in the temperature of the sulfur dioxide conveyed to separator 28 (and therefore any change in the quantity of sulfur dioxide vapors leaving said separator through line 30) will cause an adjustment of the rate of steam injection into heater 13, thereby correcting said condition, and tending to return the pressure-temperature relationships in said system to the predetermined values.

It is also clear that many other arrangements or minor modifications may be made without departing from the scope of the present invention. Thus, if desired, the steam introduced into heater 22 may also be automatically controlled, as for example responsive to the temperature of the oil-solvent mixture leaving said heater. Again, this regulation might also be responsive to the rate of flow of sulfur dioxide vapors through meter 38 in line 30.

As stated above, Fig. 2 represents a diagrammatic view showing the incorporation of the present invention into the operation of a single stage evaporating system. Referring to this drawing, the feed stock is introduced into the system through line 50 and, after passing through a constant feed valve 51, is conveyed through heat exchanger 52. The stock then passes through line 54 and steam heater 55, and is then introduced through line 56 into evaporator 57. The vaporized solvent leaves evaporator 57 through line 60, while the thus liberated oil is withdrawn through line 61, the rate of discharge being regulated by the float control valve 62. As in the case of the two-stage evaporating system described hereinabove, the vapors withdrawn through line 60 are first conveyed through heat exchanger 52 to preheat the incoming feed. The solvent is then conveyed through line 64 into separator 65 wherein the condensed portion of the solvent separates from the vapors, this condensate being removed through line 66 provided with a float control valve 67. The vapors are withdrawn from separator 65 through line 69 provided with an orifice meter 70 and a back pressure valve 71. These vapors are then conveyed through line 73 to a condenser 74. As in the case of the system shown in Fig. 1, steam heater 55 is provided with a steam input line 77 equipped with a valve 78 which may be automatically regulated by means of line 79 so that said rate of steam input into heater 55 will be responsive to the rate of flow of vapors through meter 70. The provision of the various control valves and back pressure valves in this system, as well as the regulation of the steam input into heater 55 in response to or in accordance with changes in the rate of flow of solvent vapors through line 69, permit an accurate control of the pressure-temperature conditions in the system, thus stabilizing operations and accomplishing the objects enumerated above.

Although the present invention has been described in connection with certain specific embodiments thereof, it is to be understood that there is no intention to be limited thereby, since many modifications and variations may be made without departing from the scope of the invention, which is considered to be limited only by the appended claims.

I claim:

1. A process for the recovery of solvent and oil from a solution of said oil in said solvent which comprises continuously preheating said oil-solvent solution, additionally heating said solution, introducing said heated solution under a predetermined pressure into an evaporator

whereby a portion of the solvent is evaporated, separately removing the evaporated solvent and the liquid fraction still containing a portion of the solvent, further heating the liquid fraction, conveying said heated fraction into a second evaporator maintained at a relatively lower pressure thereby causing the separation of the remaining solvent in the form of vapors, separately withdrawing said second vapors and the oil from said evaporator, conveying the vaporized solvent from the first mentioned evaporator in heat exchange relationship with the feed conveyed respectively to the low pressure and high pressure evaporators thereby preheating said feeds and causing a partial condensation of the vaporized solvent, separating the uncondensed solvent from the condensate, and regulating the additional heating of the oil-solvent solution entering the first mentioned evaporator by the variations in the rate of condensation of said first mentioned evaporated solvent.

2. In a process according to claim 1 wherein the rate of heating of the incoming oil-solvent solution is controlled to maintain the volume of uncondensed solvent leaving the heat exchange source at a predetermined minimum.

3. In a process according to claim 1 wherein the rate of introduction of the oil-solvent solution into the solvent recovery system is maintained constant, and wherein the solvent vapors leaving the high pressure evaporator, after passing in heat exchange relationship with the feeds entering both evaporators, are conveyed into a separating zone from which the condensed solvents are separately withdrawn, and wherein the rate of preheating of the oil-solvent solution entering the high pressure evaporator is controlled by the fluctuations in the rate of withdrawal of the uncondensed solvent vapors from said separating zone.

4. A process for the recovery of a solvent from a solution containing a substantial proportion of said solvent and a mineral oil of a higher boiling range than the solvent, which comprises continuously introducing the solution into a vapor-

izing zone, continuously and separately withdrawing the evaporated solvent from said vaporizing zone, passing the vaporized fraction in heat exchange relationship with the incoming solution whereby said solution is partially heated while the solvent vapors are thereby partially condensed, separating the condensed solvent from the uncondensed solvent vapors, continuously and separately removing said uncondensed vapors, further heating the incoming partially preheated oil-solvent solution, and regulating said further heating by the rate of withdrawal of the last mentioned uncondensed solvent vapors.

5. A process for the recovery of solvent and oil from a solution of said oil in said solvent, which comprises conveying the solution through two successive vaporizing zones, maintaining a higher pressure in the first vaporizing zone than in the second vaporizing zone, effecting in the first zone a partial vaporization of the solvent contained in the solution, separately removing the vapors and the unvaporized solution from said first vaporizing zone, conveying said unvaporized solution through the second vaporizing zone maintained at a relatively lower pressure thereby causing the separation of the remaining solvent in the form of vapors, separately withdrawing said vapors and oil from said second vaporizing zone, conveying the vaporized solvent from the first vaporizing zone in heat exchange relationship with the feed conveyed to the low pressure and high pressure evaporating zones respectively thereby preheating said feeds and causing the partial condensation of the vaporized solvent, separating the uncondensed solvent from the condensate thus formed, separately and continuously withdrawing said uncondensed solvent vapors, further heating the oil-solvent solution entering the first vaporizing zone, and regulating said further heating in response to the variations in the rate of production of the uncondensed solvent vapors.

EDWARD G. RAGATZ.
